SURFACE CONDENSER

Frank S. Bennett, Schenectady, N. Y., assignor
to General Electric Company, a corporation of
New York

Application November 23, 1938, Serial No. 241,981

8 Claims. (Cl. 257—43)

This invention relates to surface condensers and more particularly to surface condensers of the water cooled type.

Condensers are usually provided for receiving the exhaust from elastic fluid consuming apparatus, such as turbines, and reducing the exhaust to condensate for the purpose of conserving the boiler feed liquid and also for suitably reducing the back pressure to the consuming apparatus. Cooling water is forced through a plurality of tubes extending between headers arranged on the opposite sides of the main condenser drum and around which tubes the exhaust fluid is circulated and condensed. For high efficiency, the elastic fluid should enter the condenser with the least practical resistance and the pressure drop through the condenser should be reduced to a minimum. The non-condensables should be rapidly cleared from the heat-transfer surfaces, and removed at a low temperature with the least expenditure of mechanical energy. The condensate should also be rapidly cleared from the heat-transfer surfaces and returned to the boilers at the maximum practical temperature while the circulating cooling water should pass through the condenser with the least friction and at a relatively high velocity consistent with high efficiency. The condenser according to my invention satisfies these requirements to a higher degree than heretofore possible.

It is an object of this invention to provide a new and improved single pass condenser arrangement which is simple in design, of relatively low manufacturing cost, and highly efficient in operation.

It is a further object of this invention to provide a new and improved water cooled surface condenser of the single pass type in which a more uniform distribution of the load is obtained, the temperature of the condensate being maintained at a relatively high value while a high degree of separation of non-condensables from the water vapor is accomplished.

In the illustrated embodiment of my invention a water cooled surface condenser is provided with an arrangement of water tubes in the upper portion of the main condensing drum providing a triangular shaped passage for the elastic fluid extending the length of the drum. The elastic fluid to be condensed is directed into the space between the water tubes at the wide end of the passage while the non-condensables are withdrawn from the drum at the opposite end adjacent the coolest ends of the water tubes. The

condensate is collected in the lower portion of the main condenser drum which is in communication with the triangularly shaped passage substantially the full length of the drum so that the upper surface of the condensate is exposed to the elastic fluid passed into the condenser whereby it is maintained substantially at vacuum temperature.

For a consideration of what I believe to be novel and my invention, attention is directed to the following description and the claims appended thereto taken in connection with the accompanying drawing.

In the drawing, Fig. 1 is a longitudinal section through the condenser embodying my invention; Fig. 2 is a plan view partly in section; while Fig. 3 is a cross-sectional view of the condenser taken along the line 3—3.

Referring to the drawing, the condenser comprises a longitudinal outer shell or main condenser drum 10 which may be substantially rectangular in cross-section as indicated and which may readily be fabricated from stock material. A cooling water inlet chamber 11 is secured to one end of the shell and an outlet chamber 12 to the other end with a pair of banks 13 and 14 of water tubes communicating therebetween through the upper portion of the main condensing chamber 10. This single pass arrangement facilitates the maintenance of high cooling water velocities with a minimum expenditure of energy. Elastic fluid to be condensed is passed into the main condenser drum through the inlet 15 provided therein adjacent the outlet end of the water tubes, while non-condensables are withdrawn through the connections 16 provided adjacent the opposite or inlet ends of the water tubes. It will be noted that the two banks of water tubes are angularly arranged within the shell, being relatively close together at the water inlet end and spaced relatively far apart at the other end as shown clearly in Fig. 2 providing a triangularly or wedge-shaped passage 17 therebetween. The inlet 15 communicates with the wide end of the passage 17 which provides a low resistance entrance into the drum for the elastic fluid. Since the opposite end of the drum is maintained at a relatively lower pressure due to the action of the ejectors (not shown) which are customarily provided for extracting the non-condensables and due to the relatively cooler water tubes at that end, the elastic fluid will pass longitudinally of the drum. The passage 17 converges toward the far end as the volume of the mixture decreases due to condensation along the

banks of tubes. Baffle plates 18 are periodically arranged across the banks of tubes to prevent high velocities of elastic fluid flow longitudinally therethrough toward the outlet end. A baffle 5 plate 19 extending between the upper and lower walls of the main condenser drum is arranged transversely of the tubes adjacent the non-condensables outlet providing relatively small passages 20 between the outer edges thereof and the 10 side walls of the main condenser drum. Additional baffle plates 21 arranged parallel with the plate 19 and between it and the non-condensables outlets extend from the side walls part way through the tube banks. The mixture of non- 15 condensables and vapor passing around the edges of the baffle plate 19 is caused to flow circuitously several times across the tube banks, which at this end are relatively cool, whereby the remaining traces of vapor are condensed leaving but dry 20 non-condensables to be drawn through the outlets 16.

The water tubes may be secured in the tube sheets in any well-known manner. In the preferred embodiment, the tubes are rigidly fastened 25 therein however, with provision being made for tube expansion during operation. Screws 22 threaded into the side walls of the drum are adapted to engage with the edges of the baffle plates 18 and bow the tube banks slightly during 30 the assembly of the condenser after which they may be slackened off, or removed. Members 23 extend transversely across the condenser drum for supporting the weight of the tube banks intermediate their ends, the weight being trans- 35 mitted thereto through the sloping baffle plates 24.

During the operation of the condenser as the tubes expand, the banks slide down the plates 24, under the force of gravity, without transmitting 40 stresses to the end sheet connections. As they contract, they are drawn back up the inclined plates to the previous position. In both conditions, the weight of the mid-section of the banks is carried primarily by the supports 23 45 rather than through the tube sheets.

Since the banks of water tubes are arranged within the upper portion of the main condenser drum, a chamber 25 is provided in the lower portion thereof for the accumulation and storage of 50 condensate. The condensate chamber 25 is in communication with the passage 17 substantially throughout the length of the drum, the baffle plates 24 extending only from the side walls of the drum to the inner edges of the tube banks 55 13 and 14. A portion of the elastic fluid flowing into the condenser through the inlet 15 passes downwardly through the passage 17 and into the condensate chamber 25 impinging upon the surface of the liquid accumulated therein to maintain 60 the temperature thereof at the maximum value corresponding to the operating vacuum. The condensate draining off of the sloping edges of the baffle plates 24 effects a certain condensation of the elastic fluid within the chamber 25, the condensate being also reheated thereby substantially to the vacuum temperature. While the drainage of condensate from the storage chamber through the outlet 26 is regulated in accordance with the boiler demand, for greatest 65 efficiency in operation it is desirable that a certain quantity of condensate be maintained within the chamber 22. It is understood, however, that the upper surface of the condensate should be maintained considerably below the lower 70

tubes of the cooler banks in order that the high temperature of the condensate be maintained.

Having described the principle of operation of my invention together with the apparatus which I now consider to represent the best embodiment 5 thereof, I desire to have it understood that the apparatus shown is only illustrative and that the invention may be carried out by other means.

What I claim as new and desire to secure by Letters Patent of the United States is:

1. A surface condenser comprising a horizontally arranged longitudinal drum having an inlet adjacent one end for elastic fluid to be condensed and an outlet for non-condensables adjacent the opposite end, a pair of banks of water tubes extending longitudinally of said drum, said banks being spaced relatively wide apart at the inlet end of said drum and relatively close together at the opposite end of said drum so as to form a triangular space between said banks 20 of tubes, a water inlet chamber communicating with said banks of tubes adjacent the non-condensables outlet end of said drum, a water outlet chamber communicating with said banks of tubes adjacent the elastic fluid inlet of said drum, 25 a chamber in said drum beneath said banks of tubes in communication with said triangular space for substantially the length of said drum, said last mentioned chamber being adapted to be maintained partly filled with condensate the 30 upper surface thereof to be contacted by elastic fluid passing from said inlet through said triangular space.

2. A surface condenser comprising a horizontally arranged longitudinal drum having an inlet 35 adjacent one end for elastic fluid to be condensed and an outlet for non-condensables adjacent the opposite end, a pair of banks of water tubes extending longitudinally of said drum, said banks being spaced relatively wide apart at the inlet 40 end of said drum and relatively close together at the opposite end of said drum so as to form a triangular space between said banks of tubes, a water inlet chamber communicating with said banks of tubes adjacent the non-condensables 45 outlet end of said drum, a water outlet chamber communicating with said banks of tubes adjacent the elastic fluid inlet of said drum, an accumulator for condensate beneath said banks of tubes and in communication with said triangular space 50 for substantially the length of said drum, baffle plates arranged beneath said banks of tubes for draining the condensate from said tubes into said accumulator adjacent said passage.

3. A surface condenser comprising a horizontally arranged longitudinal drum having an inlet adjacent one end for elastic fluid to be condensed and an outlet for non-condensables adjacent the opposite end, a plurality of water tubes extending longitudinally of said drum, said tubes being so 60 arranged within said drum as to provide a triangular space extending substantially the length of said drum from said elastic fluid inlet and converging toward said non-condensables outlet, a water inlet chamber in communication with said tubes adjacent the non-condensables outlet, a water outlet chamber in communication with said tubes adjacent the elastic fluid inlet, an accumulator for condensate arranged beneath said tubes 65 communicating with said triangular space for 70 substantially the length of said drum.

4. A surface condenser comprising a horizontally arranged longitudinal drum having an inlet adjacent one end for elastic fluid to be condensed and an outlet for non-condensables adjacent the 75

- opposite end, a pair of banks of water tubes extending longitudinally of said drum, said banks being spaced relatively wide apart at the inlet end of said drum and relatively close together at the opposite end of said drum so as to form a triangular space between said banks of tubes, a water inlet chamber communicating with said banks of tubes adjacent the non-condensables outlet end of said drum, a water outlet chamber communicating with said banks of tubes adjacent the elastic fluid inlet of said drum, an accumulator for condensate beneath said banks of tubes and in communication with said triangular space for substantially the length of said drum. 5
- 15 5. A surface condenser comprising a horizontally arranged longitudinal drum having an inlet adjacent one end for elastic fluid to be condensed and an outlet for non-condensables adjacent the opposite end, a pair of banks of water tubes extending longitudinally of said drum, said banks being spaced relatively wide apart at the inlet end of said drum and relatively close together at the opposite end of said drum so as to form a triangular space between said banks of tubes, a water inlet chamber communicating with said banks of tubes adjacent the non-condensables outlet end of said drum, a water outlet chamber communicating with said banks of tubes adjacent the elastic fluid inlet of said drum, an accumulator for condensate beneath said banks of tubes and in communication with said triangular space for substantially the length of said drum. 10
- 20 15 6. A surface condenser comprising a horizontally arranged longitudinal drum having an inlet adjacent one end for elastic fluid to be condensed and an outlet for non-condensables adjacent the opposite end, a pair of banks of water tubes extending longitudinally of said drum, said banks being spaced relatively wide apart at the inlet end of said drum and relatively close together at the opposite end of said drum so as to form a triangular space between said banks of tubes, a water inlet chamber communicating with said banks of tubes adjacent the non-condensables outlet end of said drum, a water outlet chamber communicating with said banks of tubes adjacent the elastic fluid inlet of said drum, an accumulator for condensate beneath said banks of tubes and in communication with said triangular space for substantially the length of said drum. 20
- 25 25 7. A surface condenser comprising a horizontally arranged longitudinal drum having an inlet adjacent one end for elastic fluid to be condensed and an outlet for non-condensables adjacent the opposite end, a pair of banks of water tubes extending longitudinally of said drum, said banks being spaced relatively wide apart at the inlet end of said drum and relatively close together at the opposite end of said drum so as to form a triangular space between said banks of tubes, a water inlet chamber communicating with said banks of tubes adjacent the non-condensables outlet end of said drum, a water outlet chamber communicating with said banks of tubes adjacent the elastic fluid inlet of said drum. 25
- 30 30 8. A surface condenser comprising a horizontally arranged longitudinal drum having an inlet adjacent one end for elastic fluid to be condensed and an outlet for non-condensables adjacent the opposite end, means for draining condensate from said drum, a plurality of cooling fluid tubes extending longitudinally of said drum, said tubes being so arranged within said drum between said elastic fluid inlet and said non-condensables outlet as to form a triangularly shaped passage extending the length of said drum between said inlet and said outlet. 35
